UNITED STATES PATENT OFFICE.

JAMES H. TANN, OF DAYTON, OHIO.

HOISTING-JACK.

1,121,417.

Specification of Letters Patent. Patented Dec. 15, 1914.

Application filed March 5, 1914. Serial No. 822,715.

To all whom it may concern:

Be it known that I, JAMES H. TANN, a citizen of the United States, residing at Dayton, in the county of Montgomery and 5 State of Ohio, have invented certain new and useful Improvements in Hoisting-Jacks; and I do hereby declare the following to be a full, clear, and exact description of the invention, such as will enable others 10 skilled in the art to which it appertains to make and use the same.

This invention relates to new and useful improvements in hoisting jacks, and has for its principal object to provide a jack which 15 is particularly adapted for use on automobiles and similar vehicles where it is necessary at times to jack up the vehicle to enable the user to replace a wheel or perform a similar operation.

Another object of this invention is to provide a simple and effective jack from which the handle may be easily and quickly detached, thus permitting the same to be placed in a small space and occupy a minimum amount of room in the tool chest which 25 is usually carried by motor vehicles.

A further object of this invention is to provide a jack of the above type which may be easily and quickly placed in position and 30 assembled for use.

A still further object of the invention is to provide a novel means for holding the jack in the proper alinement and also providing a roller bearing which will render 35 the operation of the jack considerably easier.

With the above and other objects in view, the invention consists in the novel combination and arrangement of parts which will 40 be fully set forth in the following specification and accompanying drawings, in which,

Figure 1 is a longitudinal sectional view of a jack constructed in accordance with this 45 invention, showing the roller bearing and guide in place, Fig. 2 is a face view of a jack constructed in accordance with this invention showing the teeth and operating bar, Fig. 3 is a transverse sectional view of a jack constructed in accordance with this 50 invention taken on line 3—3 of Fig. 1, Fig. 4 is a side view in elevation showing the jack in position to be lowered, and Fig. 5 is a detail perspective view of the pawl which is 55 carried by the operating bar.

Referring now to the drawings by characters of reference, the numeral 1 designates the base of the jack having formed integral therewith the channel member 2 which comprises the rear wall 3 and the side walls 4 and 5 respectively. The rear wall of the channel member is provided with the off-set portion 6 to provide the enlarged chamber 7 at the upper extremity of the channel member. A suitable roller 8 is rotatably mounted in the channel member as at 9 and the said roller is arranged to occupy a portion of the chamber 7 when in place. A pair of forward extensions 10 and 11 are formed on the channel member and project in an opposite direction to the off-set portion 6 of the wall 3. The forward edges of these extensions 10 and 11 extend angularly as illustrated in Fig. 1 and these extensions are provided with the connecting plate 12 which is 60 formed integral therewith and is adapted to act as a stop for the locking pawl when the device is in use.

Formed integral with the walls 4 and 5 of the channel member 2 are provided the lugs 80 13 and 14 respectively which are cylindrical in form and are arranged to form pivot points for the operating lever, which will be more fully described hereinafter. These lugs 13 and 14 are arranged substantially, 85 centrally of the longitudinal extremities of the channel member as clearly shown in Fig. 2. A second set of lugs 15 and 16 are formed integral with the walls 4 and 5 respectively 90 near the free edges of said walls and are arranged to form the pivot points for the operating lever when the jack is to be lowered. A similar pair of lugs 17 and 18 are formed on the walls 4 and 5 in direct alinement with the lugs 13 and 14, but are spaced upwardly 95 from the lugs 15 and 16 to form stops for the operating lever and prevent the same from becoming displaced when the same is in position on the lugs 15 and 16.

Having described the main body portion 100 of the jack, the next in order is the lifting element which is designated generally by the numeral 19, and comprises the body portion 20 having formed at one end the curved angular extension 21 which forms a seat for the object which is to be lifted. Extending longitudinally of the body portion 20 and formed integral therewith are provided the tongues 22 and 23 which are slidable in the longitudinal groove 24 formed in the walls 105 20 of the body portion 20.

4 and 5 of the channel member 2. The body portion 20 of the lifting element 19 is arranged so that the rear wall thereof is spaced from the wall 3 of the channel member 2 and it will be apparent that the front wall of the body portion 20 will project slightly beyond the lateral extremities of the walls 4 and 5 of the channel member as illustrated in Figs. 1 and 4. This forward wall is provided with 10 the chamfered edges 25 and 26 as shown in Fig. 3. A plurality of serrations 27 are formed in the chamfered edge of the lifting element 19 and are arranged to form the teeth 28 which coöperate with the pawls in 15 holding the lifting element in the desired position.

A pawl 29 is provided and is adapted to engage the teeth 28 on the lifting member 19 and hold the lifting member in the desired 20 position. This pawl is provided with the pivot shaft 30 which projects through apertures 31 formed in the angular extensions 10 and 11. One end of the shaft 30 is bent as at 32 and provided with the weight 33 which is 25 arranged to hold the pawl normally in engagement with the teeth on the lifting member 19. An angular extension 33 is formed on the lug at its free end as shown in Figs. 1 and 4, and is arranged to release the pawl 30 by the manipulation of the handle when it is so desired.

The operating lever which has been heretofore referred to, is generally indicated by the numeral 34 and comprises the handle portion 35 which is provided with the enlarged bifurcated portion 36. This enlarged portion 36 is provided with the bifurcated extension 37 in which the pawl 38 is pivotally mounted. A transverse shaft 39 extends through apertures in the bifurcated portion, and is arranged to hold the pawl in the proper relation as shown in Fig. 1. The end of the bifurcated portion terminates in the hook members 40 which is arranged to 45 engage the lugs 13 and 14 when the device is in use. A suitable chain 41 is secured to the enlarged portion 36 as at 42 and is provided with the loop 43 which is arranged to engage the lug 33 to release the pawl 29 and 50 permit the lifting member 19 to descend.

It will be evident from the foregoing that in use, the device is assembled by placing the hook members 40 over the lugs 13 and 14 which will bring the pawl 38 in proper 55 relation to the teeth 28. Owing to the weight 32 which normally holds the pawl 29 in engagement with the teeth 28, it will be evident that when the free end of the handle portion 34 is raised, the lifting member 19 60 will be forced upwardly and in traveling in that direction the pawl 29 will engage the teeth, and as soon as the lift on the handle is released, the lifting member 19 will descend and be held in position by means of

the pawl 29. When it is desired to lower 65 the jack, the only operation necessary is to remove the handle portion from the lugs 13 and 14 and place the same on the lugs 15 and 16. The chain is then attached to the lug 33 by means of the loop 43 and upon 70 exerting pull on the chain, it will be apparent that the pawl 29 will be released from its position between the teeth in which it is in engagement and the jack will be permitted to descend. 75

From the foregoing, it will be evident that a simple and effective jack is constructed which will occupy a minimum amount of space and is capable of lifting great loads since the leverage of the handle member is 80 sufficient to force the load upwardly. Owing to the fact that the handle member is long and detachable from the body portion, it is evident that the same will occupy the least possible amount of space in a tool chest 85 or similar device which may be carried about, and for that reason the device provided is capable of being used for various purposes.

It is to be understood that the jack may 90 be lowered in the manner in which it is raised by manually releasing the pawls, and the use of a chain in this instance is unnecessary.

While in the foregoing there has been 95 shown and described the preferred embodiment of this invention, it is to be understood that such changes may be made in the combination and arrangement of parts as will fall within the spirit and scope of the 100 invention as claimed.

Having thus described my invention, I claim:

A device of the character described comprising a base plate, a channel member secured to the base plate and extending upwardly therefrom, said channel member being provided with a longitudinal groove in each of its side walls, a weight actuated pivoted pawl carried by the channel member, a 110 pair of lugs extending laterally from the channel member on each side and arranged substantially central of its longitudinal extremities, a second pair of lugs near the upper extremity of the channel member and 115 projecting laterally from the side walls thereof, said second pair of lugs being near the free edges of the side walls of the channel member, a lever adapted to engage the lugs on the channel member and thereby be 120 pivotally secured thereto, a pawl carried by the lever a hoisting element slidably in the channel member, said hoisting element being provided with a plurality of teeth on one face, the pawl carried by the channel member being adapted to engage the teeth and hold the hoisting member in adjusted position, and the pawl carried by the lever being 125

adapted to engage the teeth to raise the hoisting member, and a chain secured to the lever and adapted to engage the pawl carried by the channel member when the lever is pivoted on the second set of lugs to release the pawl and permit the hoisting element to drop.

In testimony whereof I affix my signature in presence of two witnesses.

JAMES H. TANN.
